HENRY H. ELWELL, OF SOUTH NORWALK, CONNECTICUT.

Design No. 4,430, dated October 25, 1870.

DESIGN FOR A FACE-PLATE FOR LOCKS.

The Schedule referred to in these Letters Patent and making part of the same

---

To all whom it may concern:

Be it known that I, HENRY H. ELWELL, of South Norwalk, in the county of Fairfield and State of Connecticut, have invented a new Design for Lock-Front; and I do hereby declare the following, when taken in connection with the accompanying drawing and the letters of reference marked thereon, to be a full, clear, and exact description of the same, and which said drawing constitutes part of this specification, and represents a front view.

This invention relates to a design for the ornamentation of the face of mortise locks, and consists in the matted surface with raised figures of a peculiar character, as shown in the drawing.

At each end of the plate is a screw-hole, *a*, surrounded by tracery, extending to the edges and par-

tially filling the surface of the plate to the ornamentation around the bolt-opening *A* at one end, and the latch-catch opening *B* at the other end.

The ornamentation around the last-named opening is of circular form, and that around the openings *A* and *C* square, and the space between the three openings filled with tracery corresponding to the two ends, all as fully shown in the accompanying drawing.

I claim as my invention—

The design for lock-front, as shown in the drawing and described.

H. H. ELWELL.
